RAYMOND A. HEISING, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

SYSTEM FOR THE TRANSMISSION OF INTELLIGENCE.

1,199,180.

Specification of Letters Patent. Patented Sept. 26, 1916.

Application filed October 9, 1915. Serial No. 55,048. REISSUED

To all whom it may concern:

Be it known that I, RAYMOND A. HEISING, a citizen of the United States, residing at East Orange, in the county of Essex and 5 State of New Jersey, have invented certain new and useful Improvements in Systems for the Transmission of Intelligence, of which the following is a full, clear, concise, and exact description.

10 This invention relates to improvements in the art of transmitting signals by means of high frequency electric waves.

Its object is to provide means for modulating the amplitude of a high-frequency 15 wave in accordance with the wave form of a low-frequency signal to be transmitted. This object is accomplished by impressing upon one part of the divided input circuit of a thermionic amplifier a high-frequency 20 voltage, and upon the other part of said input circuit a voltage having the wave form of the signal to be transmitted. As a result of this, there appear in the output circuit of the amplifier, under proper conditions, amplified and modulated high 25 frequency currents which may be used to supply power to an antenna or other circuit from which the signal is to be transmitted.

The possibility of so producing a modulated high-frequency current depends upon 30 the fact that the amplifying power of the thermionic repeater depends upon, and increases with, the voltage impressed upon its input terminals. If, therefore, a variable 35 voltage, corresponding to the signals to be sent, is impressed upon one part of the input circuit, and if the high-frequency alternating voltage is impressed upon another part, the high-frequency power appearing 40 in the output circuit will vary in accordance with the low-frequency signal voltage. In thus applying these two voltages, it is essential, for good quality of transmission, 45 that the change in amplification be produced by the signal voltage, so that the latter should preferably be larger or should be applied to be more effective than the high-frequency voltage. It has been found, however, that telephonic communication may be 50 maintained even if the condition is violated, but the quality is then somewhat impaired.

The circuit arrangement which has been found by experiment to be most desirable is that shown in the drawing, which represents a preferred form of this invention.

In that drawing, 1 represents any suitable generator of high-frequency power. It need not have a large power capacity, since it is required to furnish but a small high-frequency voltage. By means of the transformer 2, the electromotive force developed by generator 1 is impressed upon one grid 3, of the divided input circuit of a thermionic amplifier 4, whose other elements are a heated cathode 5, an anode 6, and a second 60 grid element 7.

8 represents a microphone, and 9 a battery by means of which it is supplied with direct current. The transformer 10, whose primary circuit contains the microphone, 70 provides that a signal voltage produced in the microphone circuit shall be impressed upon the second input element 7 of the amplifier 4.

11, 11 are batteries whose objects are to 75 insure that the electrodes 3 and 7 shall always be at negative potentials with respect to the filament 5. Under these circumstances no electrons can pass from the filament 5 to either input electrode, and 80 therefore practically no current is taken by the input circuit.

12 is another battery which maintains the space current in the amplifier between anode 85 6 and cathode 5. The output circuit of this amplifier contains the coil 13, to which is coupled another coil 14, which, in combination with condenser 15, forms a tuned circuit whose frequency may be adjusted to 90 that of the wave to be transmitted. The high non-inductive resistance 16 is preferably placed in shunt to the condenser 15, its object being to adjust the sharpness of tuning of the resonant circuit, and also to insure that the input circuits of the amplifiers, 95 next to be described, shall offer a definite impedance to incoming waves.

The amplifiers 17 are arranged in parallel and have their input circuits connected across the terminals of the resonant circuit 14, 15, the common output circuit of these amplifiers including the coil 18. The object of these amplifiers is to produce, in the output circuit, a voltage considerably larger than that appearing over their input circuits, and it is not essential that the power output of this set shall be large. The resonant circuit 19, 20, also tuned to the frequency to be transmitted, is coupled to the coil 18. The input circuits of a number 110

of amplifiers 22, arranged in parallel, are connected to the terminals of this second resonant circuit. The resistance 21 is added because it has been found to render more 5 stable the operation of the amplifiers 22. These amplifiers are especially designed to produce in their output circuits high currents, rather than high effective alternating voltages, and therefore the combination of 10 amplifiers 17 with amplifiers 22 serves to increase both the voltage and current components of the power appearing in the output circuit of the modulator element. In practice it has been found possible to employ as many as 500 amplifiers of the type 15 22. The common output circuit of amplifiers 22 is finally coupled, by means of transformer 23, to the radiating antenna 24. Any suitable receiving station may be used 20 to receive the signals thus transmitted.

The operation of the modulating amplifier 4 is as follows: High-frequency voltages impressed upon the grid 3 from the generator 1 are, in the absence of an electromotive 25 force due to microphone 8, simply repeated in enlarged form as variations of current in the output circuit. When, however, an electromotive force of the signal wave form is impressed upon the grid 7, the effect of the 30 signaling voltage is to change the amplifying power of the repeater 4, and consequently to change also the amplitude of the high-frequency current variations in its output circuit. A modulated high-frequency 35 current is therefore produced in the coil 13, and its effects are transmitted to antenna 24 by means of the intermediate apparatus, whose operation has already been described sufficiently in detail.

40 Although this invention is shown as applied to the transmission of radio signals, it is obvious that the mere substitution of a wire circuit, for example a telephone line, for the antenna 24, will permit the use of 45 this system for the transmission of modulated high-frequency waves over wire lines,

and I therefore desire to include that application as a part of my invention. It is also obvious that departures may be made from the particular circuit arrangement shown in 50 the drawing.

What is claimed is:

1. The combination in a radio transmission system, of an antenna, a source of high-frequency waves, a source of waves of signaling frequency, a thermionic repeater having an output circuit and a divided input circuit, the two parts of said input circuit being connected respectively to said sources of high-frequency waves and of low-frequency waves, of amplifying means whereby the modulated high-frequency waves in the output circuit of said repeater may be further increased in power, and a means for impressing such augmented power upon said 60 antenna.

2. In a system for the transmission of signals by means of modulated high-frequency waves, a circuit, a thermionic amplifier having an output circuit, connected 70 to said first mentioned circuit, and a divided input circuit; means for impressing high-frequency electric oscillations upon one part of said divided circuit, and means for impressing impulses of signaling frequency 75 upon the other part of said divided circuit.

3. In a system for the transmission of signals by means of modulated high-frequency waves, a circuit, a source of impulses of signaling frequency, a source of oscillations of high-frequency, and a thermionic amplifier having two grid elements, one of said elements being connected to said source of impulses, the other to said source of oscillations, and the output circuit of said 80 amplifier being so connected as to transfer power to said first mentioned circuit.

In witness whereof, I hereunto subscribe my name this 7th day of October, A. D. 1915.

RAYMOND A. HEISING.
